UNITED STATES PATENT OFFICE.

WILLIAM W. JACQUES, OF BOSTON, MASSACHUSETTS.

TELEPHONE-RELAY.

SPECIFICATION forming part of Letters Patent No. 781,207, dated January 31, 1905.

Application filed November 3, 1904. Serial No. 231,275.

To all whom it may concern:

Be it known that I, WILLIAM W. JACQUES, of Boston, in the State of Massachusetts, have invented a new and useful Improvement in 5 Telephone-Relays, of which the following is a specification.

In Letters Patent No. 767,818, issued to me on August 16, 1904, I have shown how we may by balancing the product of the telephonic resistance and capacity of a circuit by the product of its telephonic inductance and shuntage provide a telephone-circuit over which conversation may be carried on without distortion of the speech and with a minimum loss 15 in loudness. Such a circuit is called a "distortionless circuit." In a distortionless circuit, however, as in all telephone-circuits, there is a gradual attenuation or enfeeblement of the electrical undulations or telephone-waves 20 as they pass along the circuit from the near end, where the telephone-transmitter converts the speaker's vocal utterances into telephone-waves, to the distant end, where the telephone-receiver reconverts these telephone-waves into 25 vocal sounds to fall upon the listener's ear.

On very long circuits this attenuation may be so extreme that the enfeebled waves are unable to satisfactorily operate the receiving-telephone, so that conversation over such a 30 circuit becomes unsatisfactory or impossible. This attenuation is not directly proportional to the distance traversed by the waves—that is, the intensity of the wave is not one-half as great at a distance of two thousand miles as 35 it is at one thousand miles, but far less than this. In my patent above referred to I have given directions for calculating the attenuation at any given point on a given distortionless circuit, and from such calculations it appears 40 that when the attenuation on a circuit of one thousand miles is to one one-hundred-and-fiftieth of the original intensity (which still readily allows of good commercial conversation) the attenuation on two thousand miles is 45 to one twenty-two-thousand-five-hundredth, which makes the waves so feeble that conversation is quite impossible. If, however, at the end of one thousand miles we can restore the waves to their original intensity, 50 then the attenuation for the whole two thou-

sand miles will be only to one one-hundred-and-fiftieth, so that good commercial conversation may be carried on over the whole two thousand miles.

It has been proposed to reinforce telephone-waves by inserting into the circuit a relay consisting of a magneto telephone-receiver whose diaphragm acts upon a microphone so that by the introduction of fresh energy from the battery of the microphone the telephone-waves in the receiving-telephone circuit are magnified in the microphone-circuit. Experience shows that such simple relays are of little practical use, and I find the reason is that if the microphone-contacts are so heavily 65 adjusted that the reproduced waves are not distorted there is very little magnification, while, on the other hand, if the microphone-contacts are lightly adjusted, so that considerable magnification is obtained, the magnified 70 waves are so distorted in shape, the high-pitch waves being magnified out of all proportion to the low-pitch waves, that the quality of the speech becomes shrill and inarticulate, so 75 that conversation is quite impossible.

I have made in my laboratory extended studies of the variation of resistance of microphone-contacts with pressure and of the magnification of telephone-waves by microphones adjusted to various normal pressures, 80 and from these studies I have found that for very light normal pressures the microphonic resistance varies more than proportionately to the variation of pressure, so that the intensity of the waves is greatly magnified; but 85 the shape of the waves is greatly distorted, because the high-pitch waves are much more magnified than are the low-pitch waves. On the other hand, with heavy normal pressures there is comparatively little magnification; 90 but the shape of the waves is again distorted, now in the other direction, because the low-pitch waves are now magnified more than the high-pitch waves. I find that the range of normal pressure over which there is no distortion of the waves is very limited and that within these limits the magnification is very 95 small.

I have discovered that by the use of two relays, each consisting of a receiving-tele-

phone and a microphone, the receiving-telephone of the second being connected in circuit with the microphone of the first, the one relay having its parts delicately constructed 5 and its normal pressure made exceedingly light, while the other relay has its parts more massive and its normal pressure heavier, the first relay being used, essentially, to magnify the telephone-waves, while the essential function 10 of the second relay is to correct the distortion of the first, (though each multiplies the magnification and each corrects the distortion of the other,) I may by thus introducing fresh energy at one or more points 15 along a telephone-circuit restore the enfeebled waves at these points to their original intensity or even more, if desired, and without resultant distortion of their shapes, and I may even correct a not too serious distortion in 20 shape that the waves may have suffered from transmission over a long circuit which is only approximately distortionless. A "magnifying-relay" and a "correcting-relay" thus associated I will call a "compound relay." 25 By the introduction of one or more compound relays into even very long telephone-circuits of the distortionless or approximately distortionless type conversation may be carried on even between widely-separated stations 30 without serious loss either in loudness or clearness of articulation.

The operation of my compound relay may be appropriately likened to the operation of a compound microscope, the strongly-magnifying 35 but distorting relay being analogous to the strongly-magnifying but distorting "objective" of the microscope, while the more feebly magnifying but correcting relay is analogous to the more feebly magnifying but correcting 40 "eyepiece" of the microscope. As in the compound microscope, so in the compound relay, while neither objective nor eyepiece is capable of yielding considerable magnification without distortion, objective and eyepiece combined 45 enable us to obtain very great magnification without resultant distortion. In the compound microscope, as in the compound relay, each lens (or relay) magnifies, each multiplies the magnification of the other, and each corrects 50 the distortion of the other. As in the microscope additional lenses may be inserted between the objective and the eyepiece to increase the magnification, so in the compound relay additional relays may be inserted between the magnifying and the correcting relay 55 with similar effect.

My invention is founded upon my above-stated discoveries; and it consists, primarily, in the compound magnification and the correction 60 of telephone-waves by the association of two or more relays, as above described, and as hereinafter more fully described.

My invention further consists in means for so connecting two or more such compound relays 65 to the wires of the main telephone-circuit as

to magnify and correct telephone-waves transmitted over the circuit in either direction. Two compound relays associated together, one of which operates in one direction along the line while the other operates in the other direction, will be here called a "telephone-repeater." 70

My invention further consists in various details presently to be described.

In the drawings, Figure 1 is a view of my 75 compound relay shown as inserted midway of a telephone-circuit, the connecting-wires and auxiliary parts being shown diagrammatically. Fig. 2 is a horizontal cross-section of the magnifying-relay, showing the essential 80 details of construction. Fig. 3 is a front view of the microphone of the magnifying-relay as presented to the diaphragm of its receiving-telephone. Fig. 4 is a side view, partially in cross-section, showing such details of construction of the correcting-relay as are different from those of the magnifying-relay. Fig. 5 is a front view of the microphone of the correcting-relay as presented to its receiving-telephone. Fig. 6 is a diagram showing 85 two compound relays so associated with each other and midway of a telephone-circuit as to make a telephone-repeater. 90

So far as may be the same letters refer in all figures to like instruments, apparatus, 95 wires, &c., numerals being added to the letters to designate different parts of the same kind and the letters sometimes being coupled. Thus T in all cases indicates a set of telephone apparatus, t a telephone-transmitter, and r a 100 telephone-receiver. B indicates a battery, w a wire, odd numbers being usually affixed to indicate parts of the apparatus operative in one direction and even numbers parts in the other direction. Numerals are sometimes 105 used independently of letters to indicate parts of instruments or circuits and letters are sometimes used without numerals to refer generally to parts which are particularly designated by the same letter with the numeral 110 attached.

To avoid confusion, so much of the apparatus only is shown in the drawings as will enable the invention and its mode of operation to be understood. 115

In Fig. 1 the relay is shown as inserted midway between telephone - stations T' and T'', which may be assumed to be two thousand miles apart. As here shown, it is arranged to magnify the telephone-waves, which, originating at T', have passed one thousand miles over the circuit w' and w'' to the compound relay R'' and having been magnified and corrected by that relay to send them along the circuit w'' and w''' another one thousand miles to the distant telephone-station T''. 120

Rm'' is the magnifying-relay, and it consists of the receiving-telephone r''' and the transmitting telephone or microphone t''. The receiving-telephone is essentially like that in 130

general use by the American Telephone and Telegraph Company, excepting that its diaphragm d_p^3 , Fig. 2, is preferably held between concentric annular knife-edges $kn kn$, so that the spring of the diaphragm is opposed to the pull of the magnet. I find that this method of supporting the diaphragm increases its sensitiveness and accuracy of vibration in a marked degree.

10 The transmitting telephone or microphone t^3 , Fig. 1, of the relay Rm^3 consists of a granular-button microphone gb^3 , such as is in common use in the long-distance transmitters of the American Telephone and Telegraph Company, which granular button is fixed in the lead ball B^3 on the side toward the diaphragm d_p^3 and is counterbalanced by a weight cb^3 . The lead ball possesses considerable inertia. It is supported from the adjustable support 15 as^3 by the bifilar suspension-wires w^5 and w^7 , so that it is free to move toward or from the diaphragm, but not in other directions. The suspending-wires also serve as lead-wires. The telephone r^3 slides freely on an iron bed-plate B_p and may be adjusted to very delicate 20 contact with the granular button, so as to produce an exceedingly delicate light-pressure multiple-contact microphone within the granular button. At the same time the lead ball presents a considerable inertia to the vibrations of the diaphragm.

25 The microphone-circuit is completed by the battery B^3 , the primary of the induction-coil Ic^3 , and the connecting-wires, as shown. The secondary circuit of the coil Ic^3 leads directly to the receiving-telephone r^5 of the correcting-relay.

30 The correcting-relay Rc^5 is, in general, like the magnifying-relay Rm^3 , excepting that it is more massive in its construction and operation, Figs. 4 and 5. The magnet is stronger, the diaphragm is larger and thicker, and the inertia of the granular button is much greater. When in operation, the pressure between its 35 diaphragm and the granular button gb^5 , Fig. 1, is also much greater than the light pressure of the magnifying-relay Rm^3 .

35 The batteries B^3 and B^5 are preferably of the accumulator type, so as to present constant electromotive force and low internal resistance. The induction-coils Ic^3 and Ic^5 should have low-resistance primaries, while the secondary of Ic^5 should have many turns, as is customary with coils connected directly to 40 long circuits.

45 The operation of the compound relay R^3 as a whole is as follows: Telephone-waves from station T' having traveled, say, one thousand miles, and having become attenuated, say, to one one-hundred-and-fiftieth of their original 50 intensity, which still leaves them quite strong enough to actuate the relay telephone-receiver r^3 , but far too feeble to continue unaided another one thousand miles to operate the receiver of station T^2 by actuating the receiv-

ing-telephone r^3 of the magnifying-relay Rm^3 , set its diaphragm in vibration. These vibrations are by means of the light pressure and heavy inertia microphone t^3 reproduced greatly magnified and somewhat distorted in 55 the circuit $w^5 w^7 w^9 w^{11}$, which leads to the receiving-telephone r^5 of the correcting-relay Rc^5 . In virtue of the heavy pressure and inertia of the microphone t^5 of the correcting-relay the magnified and distorted waves are 60 again magnified and this time corrected, so that they are now reproduced on the farther line-circuit $w^2 w^4$, restored to the original intensity, and corrected to the original shape with which they left the station T' , and therefore ready to enter on the second stage of 65 their long journey to the distant station T^2 .

70 By sliding the receiving-telephones r^3 and r^5 of the compound relay along the surface of the heavy iron bed-plate B_p the respective 75 microphone-contacts may be each adjusted to the desired efficiency and each may be adjusted to best co-operate with the other to secure the desired magnification and correction of distortion. The bed-plate B_p is preferably supported by a springy pad S_p , so that its weight, together with the springiness of the pad, protects the apparatus from extraneous mechanical vibrations. It should be 80 enclosed by a reasonably sound-proof cover to 85 protect it from extraneous acoustic vibrations.

90 It is evident that while the compound relay as thus far described is capable of magnifying the sounds uttered into the telephone 95 at station T' so that they will be heard in the telephone at station T^2 , sounds uttered at T^2 cannot be heard at T' —i. e., the relay will not work both ways over the same circuit.

100 If we connect the wires $w' w^3$ of the first 105 one thousand miles of circuit directly with the wires $w^2 w^4$ of the second one thousand miles of circuit or, what is the same thing, bridge both the receiving-telephone of the magnifying-relay and the transmitting-telephone of the correcting-relay both between the two main circuit-wires extending from T' to T^2 , we find that the magnified waves are not only sent to line, but also into the receiving-telephone of the magnifier itself, where 110 they are of course again magnified, and this cycle of reinforcements is kept up with increasing strength until the diaphragms are forced to their elastic limits, when they continue to vibrate violently and give out a loud 115 roaring sound, determined by the normal times of vibration of the diaphragms and the associated circuits, which in no way resembles articulate speech.

120 We may, indeed, employ two complete metallic circuits extending from station T' to station T^2 and by inserting a compound relay in the middle of each circuit, each relay being inserted to operate in the desired direction, carry on a conversation between T' and 125 T^2 .

- T^2 ; but this would be expensive. In practice we may do better than this and substitute for the half of each circuit beyond the relay an inexpensive artificial circuit having the same electrical properties as the actual line on the nearer side of the relay, and then connect the outgoing circuit of each compound relay differentially through the receiving-telephone of the opposing relay. We thus have merely a single metallic circuit extending between stations T' and T^2 , with a repeater composed of two opposing compound relays and two inexpensive artificial lines inserted midway of the circuit, and over such a circuit we are enabled to carry on a loud and clear conversation. Such an arrangement of circuits is shown diagrammatically in Fig. 6. In addition to such parts as have already been designated, A^2 and A^2 are artificial lines having approximately the same distributed telephonic resistance, capacity, inductance, and shuntage as the actual lines with which they are directly connected.

The receiving-telephones r^7 and r^8 are added to preserve the balancing of the lines. They may be simply dummy relays—*i. e.*, receiving-telephones without accompanying microphones—or they may be merged, respectively, into r^3 and r^4 by placing the windings of r^7 and r^8 upon the same magnets as r^3 and r^4 or by allowing the two magnets of each relay to act upon the same diaphragm.

The operation of the repeater as a whole is as follows: Telephone-waves from station T' pass, say, one thousand miles over the actual line $w' w^3$, through the two coils of the receiving-telephones r^3 r^7 of the relay R^3 , and then through the artificial line A^2 . The outgoing waves from the relay R^3 , now restored to their original intensity, more or less, as desired, pass by wires $w^{17} w^{19}$ to the middle points of the receiving-telephones r^4 and r^8 of the relay R^4 , and the artificial line A^2 presenting the same electrical properties as the actual line $w^2 w^4$ these waves act equally and oppositely upon each of the receivers r^4 and r^8 , and so produce no effect upon the relay R^4 ; but they do act upon the telephone at station T^2 . The loss of energy due to division of the waves between the artificial line and the actual line is only one-half, which with small line attenuation and large relay magnification is a loss that in no way affects the commercial operation of the line. If desired, connection may be made to the receiving-telephones r^4 r^8 not at the middle point of the coils, but between that point and one end, and then the artificial line may be made a miniature of the actual line in accordance with the well-known principle of the Wheatstone bridge.

Having thus described the operation of the repeater in the direction from station T' to station T^2 , its operation in the opposite direction from station T^2 to station T' will from the symmetry of the diaphragm and the above-

described nomenclature be readily understood. Each compound relay of the repeater magnifies and corrects in its own direction, and each acts differentially upon its mate.

The above-described telephone-relay is especially adapted to be used in connection with circuits of the distortionless type, although, because of its above-described power of correcting a not too serious line distortion it may be used in connection with approximately distortionless circuits. The telephone-engineer to whom this specification is addressed will readily determine how far a given line may depart from the strict requirements of an ideal distortionless circuit and still be capable of satisfactory relaying if he will read in this connection my Patent No. 767,818, of August 16, 1904, referred to at the beginning of this specification.

I claim—

1. A compound telephone-relay composed of a magnifying-relay and a correcting-relay, the magnifying-relay consisting of a sensitive receiving-telephone in circuit with the incoming section of the line and adjusted to exert a light normal pressure upon the contacts of a sensitive microphone, the correcting-relay consisting of a more massive receiving-telephone in circuit, electrically, with the microphone of the magnifying-relay, and adjusted to exert a heavy normal pressure on the contacts of a heavy inertia microphone whose circuit is connected, electrically, to the outgoing section of the line.

2. A compound telephone-relay consisting of a magnifying-relay and a correcting-relay, the magnifying-relay consisting of a receiving-telephone in circuit with one section of the line, and a microphone adjusted to light normal pressure; the correcting-relay consisting of a receiving-telephone in circuit electrically with the microphone of the magnifying-relay, and a microphone adjusted to heavy normal pressure and having its circuit connected electrically to the other section of the line.

3. A pair of microphones, one adjusted to light normal pressure and the other adjusted to firm normal pressure, each provided with a separate primary circuit and a source of electromotive force therein, the one adjusted to light normal pressure having also a secondary circuit and a magnet therein adapted to vary the vibrations in said firm-pressure microphone according to vibrations set up in said light-pressure microphone.

4. A pair of microphones, one adjusted to light normal pressure and the other adjusted to firm normal pressure, each provided with a separate circuit and a source of electromotive force therein, the one adjusted to light normal pressure having also a magnet in its circuit adapted to vary the vibrations in said firm-pressure microphone according to vibrations set up in said light-pressure microphone.

5. In combination with a telephone-circuit the product of whose telephonic resistance and capacity is substantially balanced by the product of its telephonic inductance and shunt-
age, one or more telephone-relays inserted in the circuit at one or more points, whereby the attenuation of the telephone-waves traveling along the circuit is reduced or eliminated.
10. 6. In combination with a telephone-circuit in which the telephone-waves are more or less distorted, a telephone-relay adjusted to produce inverse distortion, whereby the resultant telephone-waves are undistorted.
15. 7. A telephone-repeater composed of two opposed telephone-relays, the incoming circuit of each being connected in series between one section of the line and a similarly-dimensioned artificial line while its outgoing circuit is connected differentially through the receiving-telephone of the other and thence in multiple through the other section of the line and a similarly-dimensioned artificial line.
20. 8. Four microphones arranged in pairs, each pair consisting of a microphone adjusted to light normal pressure and another microphone adjusted to firm normal pressure, each microphone of each pair being provided with a separate circuit and a source of electromo-
25
- tive force therein, the said microphones adjusted to light normal pressure having also a magnet in their said respective separate circuits adapted to vary the pressure in the said accompanying firm-pressure microphone according to vibrations set up in the said light-pressure microphone.
30. 9. In combination with a telephone-circuit and an artificial circuit having similar relative electrical dimensions, an apparatus for magnifying the intensity and correcting the shape of telephone-waves.
35. 10. A distortionless and non-attenuating telephone-circuit consisting of two line-wires divided into sections, each section having the product of its resistance and capacity substantially balanced by the product of its resistance and shuntage and being provided with a similarly-dimensioned artificial circuit, and having telephone-repeaters inserted between each two sections, each repeater having its incoming circuits in series and its outgoing circuits in multiple between the adjacent section and its artificial circuit.
